2 SHEETS—SHEET 2.

UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed June 27, 1919. Serial No. 307,212.

To all whom it may concern:

Be it known that I, MORRIS P. HOLMES, a citizen of the United States, residing at Claremont, in the county of Sullivan and 5 State of New Hampshire, have invented certain new and useful Improvements in Mining Apparatus, of which the following is a full, clear, and exact specification.

My invention relates to mining apparatus.

It has among its objects to provide an improved mining apparatus especially adapted to use in kerf cutting. A further object of my invention is to provide an improved mining apparatus equipped with improved means whereby the angle of the cutting apparatus may be varied with respect to the bottom, and wherein the elevation of the cutting apparatus may likewise be adjusted. A still further object of my invention is to provide an improved and simplified supporting means whereby the above results may be obtained, and whereby the cutting apparatus may be adjusted with great facility, the supporting and adjusting mechanism being of a simple and rugged construction which may be manufactured at small expense and, if desired, used in connection with machines of standard construction. These and other objects and advantages of my improved construction will, however, hereinafter more fully appear.

In the accompanying drawings I have shown for purposes of illustration two forms 35 which my invention may assume in practice.

In these drawings,

Fig. 1 is a side elevation of one form of my improved construction.

Fig. 2 is a vertical sectional view on line 40 2—2 of Fig. 1.

Fig. 3 is a detail transverse sectional view on line 3—3 of Fig. 1.

Fig. 4 is a detail transverse sectional view on line 4—4 of Fig. 1.

Fig. 5 is a diagrammatic side elevation showing the apparatus in one of its adjusted positions.

Fig. 6 is a diagrammatic plan view showing a preferred sequence of cuts made by an apparatus of my improved construction.

Fig. 7 is a side elevation of a modified construction.

Fig. 8 is a diagrammatic side elevation showing the same in elevated position.

In these illustrative constructions, it will 55 be observed that while the cutting apparatus may assume various forms, I have shown the same for purposes of illustration to comprise a mining machine 1 of a standard room and pillar type, which may be briefly described as including a cutter bar 2 carrying the usual cutter chain 3 and a feed driving member, herein a sprocket 4, adapted to co-operate with a flexible feeding member, herein a feed chain 5, to feed the apparatus relative to its work, both the cutting mechanism and the feeding mechanism being driven, as in a usual construction, through connections not shown, by a motor 6 carried in the machine frame. As shown in Figs. 70 1 to 6, it will also be observed that the machine 1 is removably carried on a suitable plate 7, the usual shoe 8 of the machine resting thereon and the machine being detachably clamped in position on the plate by 75 means of upstanding flanges 9 so that it may be removed for independent use whenever desired. The plate 7 is herein also swiveled at 10 on a sliding swivel support 10' slidable longitudinally of a lower horizontal truck 80 frame section 11, the support 10' herein being adapted to be clamped in any horizontal position on the frame section, by means of clamping means including set screws 10''. As shown, the machine is held in any de- 85 sired angular position with respect to the sliding swivel support 10' by means of a hole and pin connection 12, and the sliding swivel support is slidable longitudinally of the truck in either direction in a suitable 90 guideway 13 when the feed chain 5 of the machine is connected to abutments in front or rear thereof, herein including a rear chain fork 14, front chain forks 15, and rear hooks 16, the members 15 and 16 being provided on the opposite ends and sides of the truck, and the members 15 being removable.

As in a usual construction, it will also be observed that the machine 1 is operatively connected to truck wheels 17 disposed beneath the truck, by means of a power drive including a sprocket and a removable chain connection 18 driven through usual connections not shown, from a gear 19 carried on

the truck and meshing in the transport position of the machine with a gear 20 carried on the latter and driven from its motor.

In the form of my improved construction shown in Figs. 1 to 6, it will be observed that the truck 11 is provided with a lower plate 21 disposed substantially beneath the center of gravity of the machine when the latter is in transport position. This plate 21 in turn has journaled at each side thereof a plurality of transverse pivot pins 22 slightly spaced longitudinally and carrying depending angle members 23 which are slidable vertically between a plurality of cooperating upstanding angle members 24 and 25 carried rigidly by a lower section 26 of the truck frame, herein normally disposed parallel to and beneath the section 11 and forming the wheeled section of the truck frame. As shown, each of these members 23 is provided with a vertical slot 23' and a hole 23'' immediately above the same, and each member 23 is movable vertically between a pair of cooperating members 24, 25, each provided with a series of vertically arranged perforations 27 therein, adapted when registering with said slot or hole to receive one of a plurality of pins 28, herein three, as shown, connected to a three-branch chain 29. Thus, it will be observed that through the provision of the pivotal support thus formed, the frame 11 and the machine carried thereon is provided with a substantial support disposed substantially beneath the center of gravity of the machine when the latter is in transport position. Here, it will also be observed that in order further to increase the stability of the support I have provided depending members or legs 30 on each corner of the frame 11, which members extend downward between, and herein inside of, cooperating ears or projections 31 extending oppositely from the opposite ends of the lower frame 26 and adapted to be held in any desired relation to those members by means of set screws 32, the members 30 herein, as preferably, also each being braced transversely by cross bars 33 to increase the rigidity of the support.

In the use of my improved construction, it will be evident that when it is desired to vary the plane of the cutting apparatus, i. e. whenever it is desired to unload, load or insert a kerf at a different angle, this may be readily accomplished after first releasing the set screws 32 and removing the chain 18, by tilting the bar 2 and adjusting the pins 28. Here we will consider the elevating operation. When the pins at the left (Fig. 1) extend through the holes 23'' and the registering holes 27 in the members 24, 25, as they do during transport the third or unused pins may obviously be inserted at any time in the tops of the slots 23' and the registering holes in the members 24, 25

(Fig. 2). By then tilting the bar downward, the left hand members 23 are moved upward and the pins in the holes 23'' are then obviously released so that they may be removed and reinserted in the holes then registering with the holes 23'' when the bottom of each slot 23' strikes the pin therein. Obviously, if a single adjustment of this character is not sufficient, or if it is desired to adjust the machine vertically at the same time that its angle to the horizontal is altered, it will be evident that this tilting operation of the bar may be repeated in opposite directions, accompanied by successive withdrawals and reinsertions of the different sets of pins 28 as the machine is tilted. It will also be evident that where desired to simply raise the level of the machine without varying its inclination to the horizontal, such an effect may also be produced by a series of similar operations, it only being necessary for one operator to adjust the sets of pins while the other operator uses the end of the bar as a lever to tilt the machine about its center of gravity. It will, of course, be understood that when the machine has been adjusted into the desired angular position with respect to the horizontal, or in the desired vertical position, the available set screws are re-set, and that the cutting apparatus on the truck frame 11 may be unloaded or used to cut on the truck in any well known manner, for example, in the manner illustrated diagrammatically in Fig. 6, wherein its successive sumping, swinging and withdrawal cuts in an entry face are illustrated.

In the modification of my improved construction shown in Figs. 7 and 8, it will be observed that in lieu of the alternately operable pin arrangement hereinabove described, I have shown a plurality of sets of upstanding longitudinally braced supports 34 carried on the lower frame 26 and having oppositely located and serrated vertically disposed edges 35 adapted to cooperate with dog or ratchet members 36, herein, as in the case of the members 22, pivoted at 37 to a plate 38 fixed to the frame 1 and having oppositely disposed extensions 39 thereon adapted to be surrounded by and acted upon by a coiled spring 40, one spring preferably cooperating with the two dogs on each side of the truck. In this construction, it will be observed that as the machine, by movement of its bar, is successively tilted about its pivots 37, the dogs or ratchet members 36 are caused successively to engage and travel along the teeth of the serrations 35, one set of dogs being effective to support the parts as the other is moved relative to its cooperating teeth, and one set engaging the other during the operation thereof in such a manner as effectually to prevent any accidental lowering or dropping of the machine.

As a result of this construction, it will also be noted that the operator is not required to insert or renew pins during the operation of varying the inclination of the cutting mechanism or its vertical position, one operator being thereby freed. Attention is also directed to the fact that in this construction in order to provide an additional support for the frame 11 I have provided a plurality of 10 telescopically adjustable connecting rods or jacks 41 connected between the front end of the lower frame 26 and the front end of the upper frame 11, this construction, through the telescopic construction of the jacks, permitting a stable support to be provided 15 whatever the connection of the frame 11 to the lower frame 26. So far as the operation of this form of my invention is concerned, it will here be evident that in this construction 20 the machine is not intended to cut while on the truck, this form of mechanism being adapted only to vary the elevation or angle of the truck or machine for unloading purposes, or to vary the elevation or angle of the 25 truck for loading purposes.

As a result of my improved construction, it will be observed that the plane of unloading, loading, or operation of any cutting mechanism may be varied at will either 30 about a horizontal axis and relative to the horizontal, or vertically, thereby adapting the apparatus to use when desired on pitching veins or on veins or benches disposed at different horizontal levels. It will also be 35 noted that improved means have been provided herein which eliminate all necessity for providing expensive, complex and heavy constructions adjustable together vertically at each corner and each having cooperating 40 elevating means such as the power operated devices and the like which have heretofore been proposed, the construction being such that it is possible for an operator, by simply exerting pressure upon the free end of the 45 bar, which herein acts as an effective lever, to vary, as desired, the elevation of the machine, and, herein, also its angle with respect to its support. Also, it will be observed that through the provision 50 of my improved means disposed substantially beneath the center of gravity of the machine and with the sets of pivots so closely associated, it is also possible for the operator to accomplish these results 55 without any material effort, the pivoting of the machine, as set forth, and the length of the bar, enabling the adjustment to be made with great facility, one of the two usual operators, in the form of my invention shown 60 in Figs. 1 to 6, simply withdrawing and reinserting the pins 28, while the other operator exerts the desired pressure upon the end of the bar to loosen the pins and move the frame vertically; while in the form of my 65 invention shown in Figs. 7 and 8 one opera-

tor only is required to pump or jack the machine into its desired position. These and other advantages of my improved construction will, however, be clearly apparent to those skilled in the art.

70

While I have in this application specifically described two forms which my invention may assume in practice, it will be understood that the same are shown for purposes of illustration, and that the invention may be 75 modified and embodied in still further forms without departing from its spirit or the scope of the appended claims.

75

What I claim as new and desire to secure by Letters Patent is:

80

1. In a mining apparatus, a support, cutting mechanism thereon, and elevating means for the latter operable by movement of said cutting mechanism in a given plane.

85

2. In a mining apparatus, a support, cutting mechanism thereon, and means operable by movement of the latter in a given plane for supporting it at an angle to its normal position.

85

3. In a mining apparatus, cutting mechanism, a support therefor, and means operable by movement of said cutting mechanism in a given plane for selectively varying the elevation or angle thereof.

90

4. In a mining apparatus, a support, cutting means thereon, and elevating means for said cutting means operable by tilting movements of said cutting means.

95

5. In a mining apparatus, a support, cutting means thereon, and elevating means for 100 said cutting means operable by reverse tilting movements of said cutting means.

100

6. In a mining apparatus, a support, cutting means thereon, and elevating and supporting means for said cutting means successively operable by movement of said cutting means.

105

7. In a mining apparatus, a support, cutting mechanism supported thereon substantially at its center of gravity, and elevating 110 means for said mechanism operable upon a tilting movement of one of said elements.

110

8. In a mining apparatus, a support, cutting mechanism supported thereon substantially at its center of gravity, and elevating 115 means for said mechanism operable upon a tilting movement thereof.

115

9. In a mining apparatus, a support, cutting mechanism thereon, and elevating means for the latter operable upon successive 120 tilting movements thereof and including a plurality of transverse pivots.

120

10. In a mining apparatus, a support, cutting mechanism thereon, and elevating means for the latter operable by a tilting 125 movement thereof and including a plurality of closely adjacent transverse pivots.

125

11. In a mining apparatus, a support, cutting mechanism thereon, and elevating means for the latter operable by a tilting 130

130

- movement thereof and including a plurality of alternately effective transverse pivots.
12. In a mining apparatus, a support, cutting mechanism thereon, and elevating means for the latter operable by a tilting movement thereof and including a plurality of transverse pivots substantially beneath the center of gravity of said cutting means.
13. In a mining apparatus, a support, cutting mechanism thereon, a plurality of transverse pivots operatively connected to said cutting mechanism, and means for varying the points of support thereof as said cutting mechanism is reversely tilted.
14. In a mining apparatus, a support, guiding mechanism thereon, a plurality of transverse pivots operatively connected to said guiding mechanism, and means for varying the points of support thereof as said cutting mechanism is reversely tilted.
15. In a mining apparatus, a support, cutting means thereon, cutter carrying means therebetween, and elevating means for said carrying means operable upon a tilting movement of one of said last mentioned elements.
16. In a mining apparatus, a support, guiding means thereon, cutting mechanism movable on said guiding means, and elevating means operable upon a tilting movement of said guiding means.
17. In a mining apparatus, a support, guiding means thereon, cutting means guided on said guiding means, and elevating means operable upon a tilting movement of said cutting means.
18. In combination, a mining machine truck, a mining machine thereon including a cutter bar, and means for varying the elevation of said mining machine on said truck actuated by reverse movements of the free end of said bar.
19. The combination with a mining machine truck, of a mining machine thereon including a cutter bar, and elevating means for varying the angle thereof to the horizontal actuated by reverse movements of the free end of said bar.
20. The combination with a mining machine truck, of a mining machine thereon including a cutter bar, and jacking mechanism for said machine operated by reverse movements of said bar as the operating handle thereof.
21. The combination with a mining machine truck, of guiding means thereon, cutting means movable longitudinally and angularly thereof, and elevating means for said guiding and cutting means actuated by reverse movements of one of said elements.
22. In a mining apparatus, a support, cutting means thereon, guiding means for the latter therebetween, and elevating means disposed substantially beneath the center of gravity of said guiding means and operable upon a tilting movement of one of said elements.
23. The combination with a mining machine truck, of guiding means thereon, cutting means movable longitudinally and angularly thereof, and elevating means for said guiding and cutting means operable upon a tilting movement of one of said elements.
24. The combination with a mining machine truck, of guiding means thereon, cutting means movable longitudinally and angularly thereof, and elevating means for said guiding and cutting means operable upon a tilting movement of one of said elements about a transverse axis.
25. The combination with a cutter supporting means, of a support beneath the same, operative connections therebetween including a plurality of pivots, and means for successively varying the elevation of said pivots upon movement of said supporting means.
26. The combination with a cutter supporting means, of a truck beneath the latter, means therebetween including a plurality of transverse pivots for supporting said means, and means for varying the elevation of said pivotal supporting means.
27. The combination with a cutter supporting means, of a truck beneath the latter, means therebetween including a plurality of transverse pivots for supporting said means, and means for varying the elevation of either of said transverse pivots.
28. The combination with a cutter supporting means, of a truck beneath the latter, means therebetween including a plurality of transverse pivots for supporting said means, and means actuated by movement of the latter about one pivot for varying the elevation of the other.
29. The combination with a cutter supporting means, of a support beneath the same, operative connections therebetween including a plurality of transverse pivots, and means for moving said supporting means about either pivot and vertically adjusting the other pivot.
30. The combination with a cutter carrying frame, of a support therefor, and operative connections therebetween including a plurality of adjacent pivots and releasable holding means permitting vertical movement of one pivot upon a tilting movement of said frame about the other pivot.
31. The combination with a cutter carrying frame, of a support therefor, and operative connections therebetween including a plurality of pivots and releasable holding means permitting vertical movement of either pivot upon a tilting movement of said frame about the other pivot.
32. The combination with a mining ma-

chine, of guiding means therefor, a truck beneath the same, pivotal supporting means therebetween including a plurality of transverse pivots substantially beneath the center 5 of gravity of said guiding means, and means whereby the elevation of said pivots may be alternately varied.

33. The combination with a mining machine, of guiding means therefor, a truck beneath the same, pivotal supporting means therebetween including a plurality of transverse pivots substantially beneath the center of gravity of said guiding means, and means whereby the elevation of said pivots 10 may be alternately varied including means releasable upon a tilting movement of said guiding means.

34. The combination with a mining machine, of guiding means therefor, a truck beneath the same, pivotal supporting means therebetween including a plurality of transverse pivots substantially beneath the center of gravity of said guiding means, and means whereby the elevation of said pivots 15 may be alternately varied including supporting means releasable by a tilting movement of said cutting mechanism.

35. The combination with a mining machine, of guiding means therefor, a truck beneath the same; a pivotal supporting means including a plurality of transverse pivots substantially beneath the center of gravity of said guiding means, and means whereby the elevation of said pivots may be 20 alternately varied including cooperating upstanding members carried by said truck and pivotal supporting means, each having perforations therein, and pins receivable in 25 said perforations.

36. The combination with a wheeled truck, of a tiltable machine receiving frame, re-

leasable holding and elevating connections therebetween adjustable upon successive tilting movements of said frame, truck driving mechanism on said frame and operatively connected to the truck wheels, and a mining machine on said frame tiltable therewith and connectable with said truck driving mechanism. 45

37. The combination with a wheeled truck, of a tiltable machine receiving frame, a plurality of alternatively releasable pivot means between said truck and frame, frame supports in front and rear of said pivot means, means for releasably connecting said frame supports and said truck, a mining machine, a sliding swiveled support between said frame and machine, and truck driving mechanism on said frame connectable with said machine and driving the 50 truck wheels.

38. In a mining apparatus, a support, cutter carrying means thereon, elevating means disposed substantially beneath the center of gravity of the latter and operable 55 by a tilting movement thereof, and auxiliary supporting means operatively connectable between said support and said cutter carrying means at one side of said elevating means. 70

39. In a mining apparatus, a support, cutter carrying means thereon, elevating means disposed substantially beneath the center of gravity of the latter and operable by a tilting movement thereof, and auxiliary supporting means operatively connectable between said support and said cutter carrying means at opposite sides of said elevating means. 75

In testimony whereof I affix my signature.

MORRIS P. HOLMES.
